CRAIG V. MORTON, OF DAYTON, OHIO, ASSIGNOR TO DELCO PRODUCTS CORPORATION, OF DAYTON, OHIO, A CORPORATION OF DELAWARE

CHARGE FORMING DEVICE

Application filed January 21, 1930. Serial No. 422,426.

This invention relates to charge forming devices for internal combustion engines, and more particularly to devices of this character which comprise a plurality of primary carburetors, each of which delivers a primary mixture of air and fuel to one of a plurality of secondary mixing chambers located adjacent the engine intake ports and in which the primary mixture is mixed with additional air under certain operating conditions.

A device of this character is shown in the cPending application of Fred E. Aseltine, Carl H. Kindl and Wilford H. Teeter, Serial No. 288,683, filed June 27, 1928.

It has been found desirable in devices of the character disclosed in the above mentioned application, to provide means for accelerating the flow through the secondary mixing chamber past the end of the primary mixture delivery conduit to effect the necessary velocity of flow through the primary mixture passages and through the secondary mixing chambers in order to enable the engine to accelerate better and to prevent fuel precipitating out of the mixture and collecting on the walls of the secondary mixing chamber. If such precipitation of fuel takes place, it is difficult to secure equal distribution of the fuel charge to various cylinders and such precipitation is found particularly objectionable in the case of an L-head engine. In such type of engine where the fuel charge is delivered from below the valve instead of from above the valve, there is a much greater tendency for the fuel to puddle in the secondary mixing chamber than in the overhead valve type of engine, where the fuel is delivered to the cylinders from a point above the valve. In earlier devices of this same type, means have been provided to prevent the puddling of fuel in the manner described and to effect the desired velocity of flow through the primary mixture conduits, but such means have restricted the outlet branches of the manifold to such an extent as to reduce the engine power.

It is the principal object of this invention to provide means which will increase the velocity of flow through the secondary mixing chambers under all operating conditions suffi-

ciently to prevent puddling of the fuel therein, and which is so constructed that the area of the passage through said secondary mixing chambers will not be sufficiently restricted to materially reduce the engine power. While this invention is more particularly adapted to an L-head engine than to any other type, it will be obvious that its use is not limited to an L-head engine, but will to a lesser degree effect the same desired result in an engine of the overhead valve type. With this object in view, the invention consists in the provision of a Venturi tube in each outlet branch of the manifold which is automatically movable on variations of the engine speed so that the position of said Venturi tube relative to the primary mixture conduit will be varied and the restriction of the area at the delivery end of said conduit will be increased as the engine speed increases and the quantity of air flowing through the secondary mixing chamber increases.

Further objects and advantages of the present invention will be apparent from the following description, reference being had to the accompanying drawings wherein a preferred embodiment of one form of the present invention is clearly shown.

In the drawings:

Fig. 1 is a longitudinal section through a charge forming device constructed in accordance with the present invention.

Fig. 2 is a section on the line 2-2 of Fig. 1.

Fig. 3 is a fragmentary section through a branch of the manifold showing a modified form of the present invention.

The device disclosed comprises a main air manifold 10, having three outlet branches, the middle branch 12 being shown herein. Each outlet branch communicates with one of the ports of a multicylinder engine and each is provided with an attaching flange 14 for securing the manifold to the engine block in the usual manner, while a flange 16 is provided at the inlet for securing the carburetor unit to the manifold.

The carburetor unit comprises a main housing 18, having an attaching flange 20 adapted to be secured to the flange 16 by screws 22, and an air inlet coupling 24 is secured in an

opening in the upper wall of the housing to admit air thereto. A casting 26 in which the passages for supplying fuel to the nozzles are formed is secured to the lower wall of the housing 18 and a sheet metal fuel bowl 28, is held tight against the bottom of the housing in any desirable way. Fuel is conducted from a main source of supply to the fuel bowl through a conduit (not shown) and the flow of fuel to the bowl is controlled by a float 30 in the usual manner.

Fuel flows from the fuel bowl to a plurality of fuel nozzles 32 in each of the primary mixing chambers 34, the construction of which is more fully described later. Fuel is conveyed to the nozzles by a vertical fuel passage 36 to which fuel is admitted at all engine speeds by a fixed orifice 38, and at high speeds by an orifice 40 controlled by a valve 42, which is operated in the manner described in the above mentioned application. The passage 36 connects with a horizontal fuel canal 44, supplying fuel to all of the primary fuel nozzles, while at the junction of the passages 36 and 44, there is formed an enlarged chamber 46 in which is received a check valve 48 adapted to seat on the bottom of the chamber and prevent downward flow of fuel through the passage 36 whenever the suction in the mixing chambers falls, as for instance following a closing movement of the throttle.

Each fuel nozzle is provided with a main fuel outlet 50 in the top of the nozzle and a secondary fuel outlet comprising two orifices 52 and 54 in the vertical wall of the nozzle near the bottom of the mixing chamber. At intermediate and high speeds, the suction in the mixing chambers effects a flow of fuel from the main fuel outlet as well as from the secondary fuel outlets, but at idling or low speed operation under load, the suction is enough to lift fuel only to a point between the main and secondary fuel outlets, fuel flowing from the latter by the action of gravity under such conditions. Each nozzle is provided with a restricted fuel metering orifice 56.

The primary mixing chambers constitute the large anterior ends of the primary mixture passages 58 which are parallel and close together, as indicated in Fig. 2. When the carburetor is attached to the manifold, these passages register with conduits which convey the primary mixture to the secondary mixing chambers, as disclosed in the above mentioned application, the tube 60, fixed in the branch 12 of the manifold, constituting the conduit for supplying primary mixture to the secondary mixing chamber in that particular manifold branch. A restriction 62 is provided in each of the primary mixture passages immediately in advance of the fuel nozzles so as to reduce the velocity of flow past said nozzles for a purpose fully set forth in the above mentioned application.

A single throttle valve 64 which extends across all the primary mixture passages controls the flow therethrough and is provided with grooves 66, which register with said passages. The operating mechanism for the throttle is not disclosed in this application for the purpose of simplifying the disclosure, but the manner of its operation will be briefly referred to later.

Air is admitted through the coupling 24 and is controlled by a suction operated valve 68, normally held against a seat 70, by a spring 72, received between the valve and flange 74, projecting from a sleeve 76, slidably mounted on a sleeve 78, fixed in the housing and guiding the stem 80, to which the air valve is secured. The carburetor is adapted to be choked to facilitate starting of the engine by lifting the sleeve 76 into engagement with the valve, by means fully described in the above application. Sufficient air to carry the starting fuel to the intake ports is admitted through a slot 82 formed in a plate 84 secured to the main housing. The valve 68 admits air to a main air chamber 86 from which air flows to the primary mixing chambers through an opening 88 in the bottom of the air chamber and to the secondary mixing chamber through a passage 90, which connects with the inlet of the manifold 10. The flow of air through this passage is controlled by a manually operable valve 92 and a suction operated valve 94 secured to shafts 96 and 98 respectively, journaled in the housing.

The operating connections for the throttle and the valve 92 form no part of the present invention and, therefore, are not described herein, it being sufficient for the purposes of this disclosure to say that the primary throttle operates the valve 92 through the medium of an adjustable lost motion connection which permits a predetermined movement of the throttle independent of the valve 92 and is generally adjusted so as to permit the primary throttle to be moved to a position corresponding to a vehicular speed of approximately 20-25 miles per hour on the level without any accompanying movement of the valve 92. On further opening of the primary throttle, the valve 92 is moved simultaneously therewith.

On any increase of suction in the main air chamber, the valve 68 is opened to admit additional air and the opening of this valve must be retarded to prevent fluttering of the valve and to restrict the admission of air sufficiently to enrich the mixture to some extent during the acceleration period. For this purpose a dashpot is provided comprising a cylinder 100, which receives fuel from the main fuel reservoir, and a piston 102 slideable therein and secured to the stem of the air valve. The specific construction of the dashpot is not material to the present invention.

tion and any conventional form of dashpot may be employed.

As above stated, the valve 94 is opened by engine suction and a dashpot, which is not disclosed herein but is fully described in the above application, is provided to retard the opening of this valve to aid in enriching the mixture during the acceleration period, as is fully set forth in said application. In addition to the retardation of the opening of the valve 94, it has been found desirable to provide a fuel pump which is operative to supply additional fuel to the primary mixture passages during the acceleration period. The above described dashpot which controls the opening of the main air valve is utilized as a pump and a fuel delivery conduit 104 connects with the dashpot cylinder as shown in Fig. 1 and conveys fuel to a horizontal fuel channel 106, formed in a block 108, attached to the lower wall of the main housing and communicating with vertical passages 110, there being three of these passages, one of which supplies fuel to each of the primary mixture passages 58. This mechanism forms no part of this invention and is fully described in the above mentioned application.

As has been stated above, it is desirable to provide means for accelerating the flow through the primary mixture passages so that the enriched mixture following an opening of the throttle will be delivered to the secondary mixing chambers almost immediately after the throttle opens in order to secure smooth and rapid engine acceleration and to also produce a high velocity of flow through the secondary mixing chambers in order to prevent precipitation of fuel from the mixture and puddling of fuel on the walls of said secondary mixing chamber. Heretofore, Venturi tubes have been positioned in the outlet branches of the manifold, such Venturi tubes forming the secondary mixing chambers and effecting a relatively rapid rate of flow therethrough. These Venturi tubes, in earlier forms of this device, have been fixed in position with the throat of the Venturi tube adjacent the outlet of the primary mixture conduits. These devices are open to the objection that if the Venturi tube is made sufficiently small at the throat to produce the desired acceleration of flow when the throttle is only slightly opened and a small quantity of air passing through the tube, such tube will restrict the flow when the throttle is relatively wide open to such a degree that a relatively high partial vacuum is created within the tubes and a consequent reduction in engine power results.

According to the present invention, Venturi tubes are employed in the outlet branches of the primary manifold and such tubes are normally positioned, when the throttle is closed or nearly closed, so that the throat is

closely adjacent the outlet of the primary mixture conduit. These Venturi tubes, however, are automatically movable as the quantity of air passing through the said Venturi tubes increases with the opening of the throttle, so that the throats of the Venturi tubes are moved away from the end of the primary mixture conduit and the area of the available passage through which air must flow is increased in accordance with the increase in opening of the throttle.

For this purpose, each outlet branch of the manifold is provided with a sleeve 120, which fits relatively tightly within the manifold branch and at its end adjacent the engine, is bent over as shown in Fig. 1 to form an inner sleeve 122, a space 124 being provided between the two sleeves. A Venturi tube 126 is slidably mounted within the sleeve and is provided with a cylindrical extension 128 which is received within the space 124 and fits relatively tightly in said space. The sleeve 120 is adapted to be held in position by a set screw 121 or any other suitable means, and threaded or otherwise secured in sleeve 120 is a collar 130, which limits the movement of the Venturi tube in one direction and determines the normal position when the engine is not running. Received within the space 124 between the end of the cylindrical extension 128 and the closed end of the sleeve 120 is a spring 132, which normally moves the Venturi tube into engagement with the collar 130. Holes 134 are provided in the inner sleeve 122 to permit the escape of air from the space 124. As above stated, the cylindrical extension 128 fits relatively tightly within the space 124 so that such extension and the space constitute an air dashpot which retards the movement of the Venturi tube in either direction of its movement, the tube being enabled to move only as rapidly as the air can pass out of or into the space 124 through the orifices 134 and by leakage around the extension 128.

The operation of this device should be obvious on inspection. Normally, the Venturi tube is in the position shown in Fig. 1 with the throat of the tube adjacent the end of the primary mixture conduit. If the throttle is opened, a greater quantity of air flows through the venturi and this air in conjunction with the suction of the engine, moves the venturi to the right in Fig. 1, and the throat of the venturi away from the end of the primary mixture conduit, increasing the area of the passage between said conduit and the venturi. The motion of the venturi is retarded by the action of the above described air dashpot so that the movement of the venturi is gradual and no damage to the parts is effected due to the rapid pulsations of the engine and consequent rapid changes in suction. As the throttle is moved toward closed position, the venturi is gradually moved in

the opposite direction until it reaches the position shown in Fig. 1. This device, therefore, accelerates the flow through the secondary mixing chambers at all times when the engine is running, but since the area of the passage therethrough is increased as the quantity of air flowing through the chamber is increased, the partial vacuum maintained therein is held substantially constant and the power of the engine is not reduced.

In Fig. 3 is shown a somewhat modified form of the above described means for accelerating the air flow through the secondary mixing chamber and in this form the venturi is provided with a cylindrical extension 140 at its rear end which slides within a space 142 similar to the space 124. This space is also provided with a spring 144, which in conjunction with the spring 132, causes the venturi to be in effect, a floating venturi, its normal position being determined by the relative strength of the two springs so that the venturi comes to rest when the springs reach a condition of balance.

25 While the form of embodiment of the present invention as herein disclosed, constitutes a preferred form, it is to be understood that other forms might be adopted, all coming within the scope of the claims which follow.

30 What is claimed is as follows:

1. An intake manifold for a multicylinder internal combustion engine having a plurality of intake ports, comprising a plurality of outlet branches adapted to communicate with said intake ports, movable means adapted to reciprocate in said branches for controlling the velocity of flow therethrough and means for cushioning the movement of movable means in both directions of its movement.

40 2. An intake manifold for a multicylinder internal combustion engine having a plurality of intake ports, comprising a plurality of outlet branches adapted to communicate with said intake ports, movable means in said branches for controlling the velocity of flow therethrough, and a dash-pot for retarding the movement of said movable means.

3. An intake manifold for a multicylinder internal combustion engine having a plurality of intake ports, comprising a plurality of outlet branches communicating with such ports, conduits adapted to supply fuel to said manifold branches, a movable member in each of said branches adapted to regulate the velocity of flow past the ends of said conduits, means normally holding said member in position to restrict the passage through said outlet branch at a point adjacent the outlet of said fuel supply conduits and means for retarding the movement of said movable member.

4. An intake manifold for a multicylinder internal combustion engine having a plurality of intake ports, comprising a plurality of outlet branches communicating with such

ports, conduits adapted to supply fuel to said manifold branches, a movable member adapted to be moved toward and away from the outlet end of each of said fuel delivery conduits to regulate the velocity of flow past the end of said conduit, and means for retarding the movement of said movable member in both its directions of movement.

5. An intake manifold for a multicylinder internal combustion engine having a plurality of intake ports, comprising a plurality of outlet branches communicating with such ports, fuel delivery conduits projecting into the outlet branches of said manifold, a movable member in each of said branches having a restriction therein, and means normally holding each of said member in such position that the restriction therein is adjacent the outlet end of its associated fuel delivery conduit.

6. An intake manifold for a multicylinder internal combustion engine having a plurality of intake ports, comprising a plurality of outlet branches communicating with such ports, fuel delivery conduits projecting into the outlet branches of said manifold, a movable member in each of said branches having a restriction therein, means normally holding each of said members in such position that the restriction therein is adjacent the outlet end of its associated fuel delivery conduit, and means for retarding the movement of said movable members.

7. An intake manifold for a multicylinder internal combustion engine having a plurality of intake ports, comprising a plurality of outlet branches communicating with such ports, fuel delivery conduits projecting into the outlet branches of said manifold, a movable member in each of said branches having a restriction therein, said members being normally positioned so that the restriction therein is adjacent the outlet end of the fuel delivery conduit, and adapted to be moved by engine suction to vary the area of the passage at the end of said fuel delivery conduit.

8. An intake manifold for a multicylinder internal combustion engine having a plurality of intake ports, comprising a plurality of outlet branches communicating with such ports, fuel delivery conduits projecting into the outlet branches of said manifold, and movable Venturi tubes within said branches surrounding said conduits, said Venturi tubes normally being positioned so that the throats thereof are adjacent the associated fuel delivery conduits.

9. An intake manifold for a multicylinder internal engine having a plurality of intake ports, comprising a plurality of outlet branches communicating with such ports, fuel delivery conduits projecting into the outlet branches of said manifold, suction operated Venturi tubes in said manifold surrounding said conduits and adapted to be

moved as the engine speed varies to vary the size of the passage between each fuel delivery conduit and its associated Venturi tube.

10. An intake manifold for a multicylinder internal combustion engine having a plurality of intake ports, comprising a plurality of outlet branches communicating with such ports, fuel delivery conduits projecting into the outlet branches of said manifold, suction operated Venturi tubes in said manifold surrounding said conduits, and means for retarding the movement of said Venturi tubes.

15. In combination with the intake pipe of an internal combustion engine having an intake port, a conduit for supplying a primary mixture of fuel and air to said intake pipe and means in said pipe for increasing the velocity at which the mixture is delivered from said intake pipe to the intake port, said means comprising a movable passage restricting member and means for retarding the movement thereof.

20. In combination with the intake pipe of an internal combustion engine having an intake port, a conduit for supplying a primary mixture of fuel and air to said intake pipe and means in said pipe for increasing the velocity at which the mixture is delivered from said intake pipe to the intake port, said means comprising a movable Venturi tube, adapted to variably restrict the pipe as it moves to different positions.

25. In combination with the intake pipe of an internal combustion engine having an intake port, a conduit for supplying a primary mixture of fuel and air to said intake pipe and means in said pipe for increasing the velocity at which the mixture is delivered from said intake pipe to the intake port, said means comprising a suction operated Venturi tube adapted to be moved to different positions as the engine speed varies.

30. In combination with the intake pipe of an internal combustion engine having an intake port, a conduit for supplying a primary mixture of fuel and air to said intake pipe and means in said pipe for increasing the velocity at which the mixture is delivered from said intake pipe to the intake port, said means comprising a movable Venturi tube adapted to variably restrict the pipe and means for retarding the movement of said

35. Venturi tube.

40. In combination with the intake pipe of an internal combustion engine having an intake port, a conduit for supplying a primary mixture of fuel and air to said intake pipe and means in said pipe for increasing the velocity at which the mixture is delivered from said intake pipe to the intake port, said means comprising a movable Venturi tube adapted to variably restrict the pipe,

means for retarding the movement of said Venturi tube and means for returning the said tube to its normal position.

45. In combination with the intake pipe of an internal combustion engine having an intake port, a conduit for supplying a primary mixture of fuel and air to said intake pipe and means in said pipe for increasing the velocity at which the mixture is delivered from said intake pipe to the intake port, said means comprising a movable Venturi tube adapted to variably restrict the pipe, an outer sleeve in which said tube is slidale, an inner sleeve parallel to said outer sleeve throughout part of its length and spaced therefrom, a projecting portion of the Venturi tube extending into the space thus formed, means closing the other end of said space and means permitting only a limited passage of air to and from space whereby it acts as a dashpot to retard the movements of the Venturi tube.

50. In combination with the intake pipe of an internal combustion engine, of a removable unit adapted to be inserted in said pipe adjacent its outlet end to control the velocity of flow through said pipe into the intake ports, said unit comprising a sleeve fitting within the intake pipe, a Venturi tube slidale within the sleeve, means positioned at one end of the sleeve to retard the movement of said Venturi tube, a stop at the other end of the sleeve for determining the normal position of the venturi and means for retaining the sleeve in position in said intake pipe.

In testimony whereof I hereto affix my signature.
